UNITED STATES PATENT OFFICE.

ORRELL ASHTON, OF SWAMPSMOTT, MASSACHUSETTS, ASSIGNOR TO UNITED SHOE MACHINERY COMPANY, OF PATERSON, NEW JERSEY, A CORPORATION OF NEW JERSEY.

MACHINE FOR USE IN THE MANUFACTURE OF BOOTS AND SHOES.

1,113,086.

Specification of Letters Patent.

Patented Oct. 6, 1914.

Application filed June 13, 1912. Serial No. 703,476.

To all whom it may concern:

Be it known that I, ORRELL ASHTON, a citizen of the United States, residing at Swampscott, in the county of Essex and 5 State of Massachusetts, have invented certain Improvements in Machines for Use in the Manufacture of Boots and Shoes, of which the following description, in connection with the accompanying drawings, is a 10 specification, like reference characters on the drawings indicating like parts in the several figures.

This invention relates to machines for use in the manufacture of boots and shoes and 15 particularly to shoe shaping machines.

The invention is herein shown as embodied in a shoe beating machine, and this application is a continuation of my application Ser. No. 406,213, filed Dec. 12, 1907, 20 which matured June 25, 1912 into Letters Patent No. 1,030,837, as to subject matter common to this application and to said application Ser. No. 406,213. The machine shown in the said prior application comprises a rotary beater which has a rapidly 25 rotating carrier or hub having annular end disks, between which disks extend stems or rods arranged around the periphery of the carrier and supporting a series of beating 30 elements which strike a very rapid succession of light blows. The beating elements specifically claimed therein comprise rings loosely strung on their supporting rods so that, during the rotation of the carrier, the 35 rings are held out radially therefrom by centrifugal force in normal operative position while, under pressure of the work, the rings are capable both of swinging or turning about their pivots and of yielding inwardly. 40 Rotary shoe beating machines of this type are employed with great success in pounding up the overlasted marginal portions of shoe upper along the edges of the shoe bottom. While the beating elements of the said machine are from their above outlined construction and mounting well adapted to conform to the surface of the work presented to them and are efficient in pounding up and smoothing the work, I have discovered 45 that certain advantages may be obtained by a construction and mounting of beating elements such that, in addition to the above mentioned movements, the beating elements 50 may have movements in other directions, in-

cluding a sidewise movement through displacement in a direction lengthwise of the carrier as they strike the work. 55

In accordance with the present invention, the beating elements comprise blocks loosely confined against dislodgment from the rotary carrier by centrifugal force and constructed and arranged with relation to the said carrier to have a practically universal turning and swinging movement as they strike the work, in addition to capacity for 60 yielding inwardly under pressure of the work. Beating elements thus constructed and arranged are capable not only of yielding inwardly radially, but also sidewise or laterally and, at the same time, of swinging 65 or tipping backwardly as they strike the work and rub over it. 70

The machine also comprises other instrumentalities for treating a shoe, besides the beating roll, including a smoothing or ironing roll and another feature of this invention consists in improved shoe supporting and guiding means particularly adapted to coöperate with these beating and smoothing rolls. A work guide which I have found 75 particularly adapted for coöperation with the beating roll while the latter is treating the bottom of the shoe comprises a work resting table or plate which is normally disposed horizontally and can tip about an 80 axis parallel with the axis of the roll. Another work guide, which I have found particularly adapted for coöperation with the smoothing roll by pressing the side of the shoe against said roll and which may also 85 be used with advantage to press either the side or the bottom of the shoe against the face of the beating roll, comprises a work resting plate or bar that is also pivoted about an axis substantially parallel with the 90 axis of the roll and over which the shoe may slide as it is presented progressively to the action of the roll. Preferably both rests are yieldingly upheld and the shoe can be 95 wedged between the work resting bar and the roll while the bar presses the shoe against the roll. Either or both rests may be vibrated and thereby caused to effect a light beating action upon the surface of the shoe engaged thereby. Herein, the work 100 resting table is shown as vibrated, being held yieldingly away from the vibrator when the work is not pressed against it, and it will 105

be obvious that similar vibrating means could be applied to the work resting bar. It will also be observed that the action of the beating roll upon the shoe produces a 5 vibration of the shoe against the supporting face of the shoe resting means by which the surface of the shoe engaged by said resting means is lightly beaten whether or not the resting means is vibrated. The beating action 10 of the shoe resting means is particularly advantageous and the coöperation of the resting means and the rolls is conspicuously apparent, when a lasted welt shoe is presented with a side face against the roll and with 15 that portion of its bottom face over which the welt is to be applied against the resting means. The vibration of the resting means, or of the shoe, then beats the upper firmly against the feather of the innersole lip. The 20 resting plate or bar may advantageously have a formation to adapt it to beat the upper into the angle between the feather and the lip of the innersole to form there a seat for the welt. It is obvious that work resting 25 plates or bars having formations adapted for the particular work to be done may be used exchangeably in coöperation with the rolls for treating the sides of the shoe.

These and other novel features of the 30 present invention, including certain combinations of parts and details of construction, will be apparent from the following detailed description read in connection with the accompanying drawings in which:—

35 Figure 1 is an angular perspective in elevation of portions of the machine concerned with the present invention; Fig. 2 is an end view in elevation and partly in section of the machine showing two positions in which 40 the work is presented for beating the forepart of a McKay shoe; Fig. 3 is a detail of one of the beating elements; Fig. 4 is a side elevation partly in section of a portion of the machine showing a position of the work 45 for beating the rear part of the shoe while using the work rest that is illustrated in Fig. 1 for supporting the forepart; Fig. 5 is a detail showing a work resting plate particularly adapted for welt shoes and its 50 operative relation to the beater and a welt shoe forepart; Fig. 6 is an angular perspective of the work resting plate on a larger scale and looking at the bottom of the plate; Fig. 7 is an angular perspective in elevation 55 and on a similar scale of the support on which said plate may be hinged; Fig. 8 is an angular perspective of another form of work supporting means, looking at the work support from below; Fig. 9 is a vertical section 60 through the smoother roll, showing an operative relation of said roll and the co-operating shoe resting means to a shoe; Fig. 65 10 is an extension of the left hand end of Fig. 1, the angle being changed to increase the disclosure; Fig. 11 is an end elevation

particularly to show the features illustrated in Fig. 1.

Bearings 2 on the frame of the machine support a shaft 4 operated through suitable connections to a source of power and upon 70 which is mounted the shoe beating and finishing rolls with which this invention has to do, including a hub or carrier having end disks or flanges 6. The end disks 6 are connected by rods 8 which support an annular 75 series of beating members, each comprising a plurality of beating elements 40.

The beating elements 40, in accordance with a feature of the present invention, somewhat resemble dumb-bells in shape, 80 having at their outer ends rounded heads 42 (Figs. 2 and 3), the outer faces of which constitute work engaging surfaces, and having at their inner ends ball shaped flanges 45. Reduced necks 44 connect the heads 42 and 85 the flanges 45. The beating elements 40 are loosely confined between adjacent rods 8 arranged on opposite sides of the necks 44. The beating elements are thus free during rotation of the carrier to be moved outwardly under the action of centrifugal force 90 but are prevented from being thereby dislodged from the carrier by reason of their flanges 45. While the beating elements 40 are thus held outwardly their above-described construction and mounting permits them, under pressure of the work, to yield inwardly, radially or otherwise. Moreover, the ball shaped flanges 45, in connection with the supporting rods 8, constitute the substantial equivalents of ball and socket joints 100 and permit practically universal turning or swinging movement of the beating elements, so that the beating elements not only may swing backwardly as they strike the 105 work and yield inwardly, but are also capable of having a sidewise or lateral movement lengthwise of the carrier in either direction.

As shown in Figs. 1 and 2, the above described rotary beater may be advantageously employed for beating the bottom of a shoe in conjunction with a side beater comprising a plate 10 connected with suitable operating mechanism and arranged to extend into close proximity to the beating elements 40 where it is adapted to engage the side of the shoe close to the edge of the shoe bottom.

In addition to the upper beating roll, which will preferably be constructed with 120 beating elements 40 as above described, the machine comprises an upper smoothing roll 11 which will preferably have the contour shown in Figs. 1 and 10 to adapt it particularly for treating various portions of the 125 sides and top of the shoe.

Coöperating with the upper beating and smoothing rolls are means for resting the shoe in position to receive progressively the 130 action of said rolls on one side of the shoe

while the shoe is advanced along and, it may be, actively treated by the resting means, which will preferably be hinged to tip toward and from the rolls about an axis substantially parallel with the axis of the rolls. In Figs. 1, 2, 4, 5 and 6 the resting means cooperating with the beating roll is shown as comprising a tipping plate 12, and in Figs. 1, 9, 10 and 11 the resting means cooperating with the smoothing roll 11 is shown as a tipping bar 13, although for some operations said resting means may be interchanged, or similar ones may be used to cooperate with both rolls. The plate 12 is shown as hinged to a head 14 having a stem 16 and may have any suitable formation of work resting face, either broad and plane as in Figs. 1, 2 and 4 if the machine is to be used for beating and smoothing McKay shoes, or narrow, or having a raised abutment which constitutes the actual work resting face, as in Fig. 5 (see also Fig. 8) for welt work, the face in the latter case engaging the shoe bottom between the edge and the lip of the welt innersole to assist in forming the upper upon the feather of the innersole to provide a good seat for the welt with which the shoe is later to be provided. Preferably, and as shown, the tipping plate 12 has associated with it a stop 46 arranged to limit the extent of tipping movement of the plate 12. The shoe resting bar 13 (Fig. 9) is adapted similarly to support and act on a shoe while it is being treated by the roll 11, or it might be by the beating roll. Provision is made for vibrating the work rest in a direction substantially perpendicular to the supported surface of the shoe to cause it to act more effectively in forming the shoe stock. The vibrating means is illustrated as applied to the resting plate 12 and it will be obvious that it may be similarly applied to the resting bar 13. The stem 16 can slide in a sleeve 18 and be depressed when desired, against the action of a spring 20, into the path of a continuously running cam 26 on a counter shaft 28 mounted in bearings 30 and driven by a pulley 32 and a belt from a pulley 34 on the high-speed shaft 36 from which the side beater 10 is vibrated. The collar 37 limits the elevation of the stem 16 by the spring 20 and an adjustable stop 38 limits the depression of the stem and may be set to hold the stem of the rest out of the path of the cam 26, if vibration of the rest is not desired. It may be noted that the action of the beating elements 40 produces some vibration of the shoe against the rest and thereby increases the smoothing effect of the rest upon the surface engaged by it. Furthermore, the beating elements 40 have operative movement in a direction to work the upper stock toward the edge formed by the side and bottom faces of the shoe. This action of the beating elements 40 in conjunction

with the coöperating vibratory action of the rest when that rest is vibrated results in forming between the side and bottom faces of the shoe the well defined angular edge which is so important in the finished shoe. The rest shown in Fig. 8 may be substituted for that shown in Fig. 4, the stems being alike, and the shoe resting plate in Fig. 8 is not hinged but is adjustable horizontally on the head of its stem and the contour of its shoe resting surface is made to adapt it particularly to the work illustrated in Fig. 5, or that indicated in Fig. 4. The work resting bar 13 of Figs. 9, 10 and 11 is a convenient embodiment of the invention for use with the smoothing roll 11, which it is customary to make of irregular tapering formation as appears in Fig. 10 because it can be more readily adapted to suit the configuration of the roll than can the plate 12. The shoe resting bar 13 is shown as having two stems 66 which are adjustably clamped in blocks 68 by bolts 70 to permit adjustment lengthwise of the stems. The blocks 68 can turn on a rod 82 which is encircled by a sleeve 72 that is clamped against turning in support 76 by a binding screw 77. A torsion spring 84 has one end connected to one block 68 and the other to the sleeve and yieldingly upholds the shoe resting bar 13 to a position determined by a stop screw 86 that is carried by a fixed rod 90 and engages an ear on the upper end of one block 68 as shown in Figs. 10 and 11. The support 76 is adjustable angularly about a rod 78 that is located back of the rod 13 and projects from a portion 80 of the frame 2. The specific construction and mounting of this shoe resting means is not herein claimed but will be claimed in a separate application.

In the use of the machine, the shaft 4 and the rolls and other driven parts being in motion, a shoe may be presented in positions such as indicated in the several figures of the drawings and turned and advanced until all parts requiring treatment have been subjected to the action of the beating roll and of the smoothing roll for pounding up and blocking the shoe as its condition may require. If the shoe is a welt shoe, the resting plate 12 of Fig. 5 will advantageously be used rather than that shown in Fig. 2 to shape the upper to the feather of the innersole, and it may be into the angle between the feather and the lip, without crushing the innersole lip. If beating by means of the shoe resting plate (Figs. 4, 5 or 8) is desired, the stop screw 38 will be lowered to allow the stem 16 to be depressed into the path of the cam 26. When the shoe has been beaten the operator shifts it to the smoothing roll 11, resting it on the bar 13 as in Figs. 9 and 11 to cause the sides and top faces of the shoe to be treated by rubbing action in the direction desired, either toward

130

the edge as in Fig. 9 or lengthwise of the edge as in Fig. 11. In the latter treatment the shoe can be thrust toe first between the bar and the roll to treat one side as in dotted lines in Fig. 11, the spring 84 yielding and serving to press the shoe upwardly against the roll while the shoe is in that position in which the operator least advantageously applies such pressure, and then can be with-
10 drawn and advanced in its full line position for treatment of its other side while the operator presses the shoe downwardly. The type of machine to which this invention relates is identified in the claims as a shoe
15 shaping machine and the beating and smoothing rolls are sometimes identified as shoe shaping rolls but without any intention to exclude shoe making and finishing machines having rolls or tools, the operations of which may not be strictly described as giving shape to a shoe.

Having thus fully explained my invention and in what manner the same may be embodied, what I claim as new and desire
25 to secure by Letters Patent of the United States is:

1. In a machine for shaping shoes, a rotary carrier, operating means therefor, a plurality of supporting members on the carrier, and a plurality of beating elements each loosely confined by two adjacent supporting members to permit bodily movement of said elements outwardly under the influence of
30 centrifugal force during the rotation of the carrier and inwardly under pressure of the work.

2. In a machine for shaping shoes, a carrier, operating means therefor, a plurality of beating elements each comprising a beating portion, a relatively narrow neck and a retaining head, and retaining means embracing the neck and permitting the beating elements to tip in different directions in
35 planes angularly related to one another.

45 3. In a machine for shaping shoes, a carrier, operating means therefor, a plurality of beating elements and a plurality of supporting members connected to the carrier and arranged to confine the beating elements to the carrier while permitting sidewise movement of individual beating elements lengthwise of the carrier to adapt the beating elements to conform to the surface of the work as they strike the work and rub
50 over it.

60 4. In a machine of the class described, a rotary carrier and a series of beating elements each having flanges on its inner end and loosely supported in the carrier and confined against dislodgment from the carrier under the action of centrifugal force by
65 said flanges.

5. In a machine of the class described, a carrier and a plurality of beating elements
65 having ball flanges on their inner ends and

pivotedly supported in the carrier by said flanges to permit universal tipping movement as the beating elements engage and rub over the work.

6. In a machine of the class described, a rotary carrier, a plurality of rods on the carrier and a series of beating elements, having at their outer ends heads formed to present work engaging surfaces and having retaining flanges at their inner ends and reduced necks between their ends adapted to be loosely held between adjacent rods arranged on opposite sides of the said necks.
70

7. In a machine of the class described, the combination with a rotary carrier and a plurality of rods arranged around the periphery of the carrier, of the beating elements 40, having the necks 44 and flanges 45, the said beating elements 40 being confined loosely between adjacent rods on opposite
75 sides of their said necks, substantially as described.
80

8. A shoe shaping machine having, in combination, a roll for treating one side of a shoe and a shoe resting plate for engaging a side of the shoe that is substantially perpendicular to the first mentioned side, said plate being mounted to move about an axis which is laterally removed from the side of the roll engaging the shoe and which extends substantially parallel to the axis of rotation of the roll.
90

9. A shoe shaping machine having, in combination, a roll for treating one side of a shoe and a rest which extends into proximity to the roll for engaging the bottom of the shoe adjacent to its edge and is arranged to uphold and sustain the shoe for the action of the roll, the rest being mounted to move about an axis substantially parallel
95 with the axis of the roll to permit presentation of the side of the shoe in different relations to the roll.
100

10. A shoe shaping machine having, in combination, a roll for treating one side of a shoe, a work receiving rest which is yieldingly held in operative position to support the shoe for the action of said roll and is movable about an axis that is substantially parallel with the axis of the roll, and means
110 for limiting movement of the rest.
115

11. A shoe shaping machine having, in combination, a roll for treating one side of a shoe, power driven means for rotating the roll, and a shoe receiving and supporting rest which has a shoe bottom engaging face of less width than the feather of the innersole and is arranged relatively to the roll to engage a lasted shoe between the innersole
120 lip and the edge of the shoe bottom.
125

12. A shoe shaping machine having, in combination, a roll for treating one side of a shoe, power driven means for rotating the roll, a shoe receiving and supporting rest which is arranged to support the shoe for the
130

action of said roll and is shaped to engage the bottom of a lasted welt shoe between the edge of the shoe and the innersole lip, and means for vibrating the rest.

5 13. A shoe shaping machine having, in combination, a roll for treating one side of a shoe adjacent to the edge formed between that side of the shoe and a side of the shoe that is substantially perpendicular to the 10 first mentioned side, and having operative movement in a direction to work the stock toward the said edge, a rest for engaging the second named side of the shoe adjacent to the said edge, and automatically operating 15 means for relatively vibrating the rest and the shoe to shape the surface of the shoe engaged by the rest.

14. A shoe shaping machine having, in combination, a roll for treating one side of a 20 shoe, power driven means for rotating the roll, a rest which is arranged to engage the bottom of a lasted welt shoe between the lip of the innersole and the edge of the shoe that is adjacent to the roll and which has a 25 formation to press the upper into the angle between said lip and the feather of the innersole, and means for vibrating said rest to shape the upper into said angle while the roll shapes the upper on the side of the shoe.

30 15. A machine for shaping lasted shoes having, in combination, means continuously and uninterruptedly acting on the side of the shoe and having operative movement in a direction to work the stock toward the edge 35 of the shoe bottom, and means formed and arranged to engage the shoe bottom between the edge and the lip of a welt innersole to shape the upper against the feather of the innersole.

40 16. A machine for shaping lasted shoes having, in combination, a roll acting on the side of the shoe and toward the edge of the shoe bottom, means having operative movement in a direction substantially at right 45 angles to the direction of operative movement of the roll and formed and arranged to engage the shoe bottom between the edge and the lip of a welt innersole, and means to vibrate the shoe bottom engaging means to 50 shape the upper against the feather of the innersole.

17. A machine for shaping lasted shoes having, in combination, continuously running means acting on the side of the shoe 55 and having operative movement in a direction to work the stock toward the edge of the shoe bottom, means formed and arranged to engage the shoe bottom between the edge and the lip of a welt innersole, and means for

actuating the shoe bottom engaging means to hammer the upper into the angle between the lip and the feather of the innersole.

18. A machine for shaping lasted shoes having, in combination, a roll acting on the side of the shoe to block the shoe, a rest provided with an upstanding abutment formed and arranged to engage the shoe bottom between the edge and the lip of a welt innersole, and means for actuating the rest for beating the upper against the feather of the 70 innersole.

19. In a machine of the class described, a beater for beating the upper on the side of the shoe at and adjacent to the edge formed by the side and bottom face of the shoe, a 75 rest for engagement with the shoe bottom, means for operating the beater in contact with the side of the shoe in a direction toward the rest, and means for reciprocating said rest to cause it to beat the bottom of 80 the shoe while the side beating means is treating the side of the shoe.

20. In a machine of the class described, a beater for beating the upper on the side of a shoe at and adjacent to the edge formed by 85 the side and bottom faces of the shoe, a normally stationary shoe bottom rest, arranged to sustain the shoe against displacement in the direction in which the beater acts upon it, and means for operating said rest at the 90 will of the workman to beat the bottom of the shoe while the side beater is beating the side of the shoe.

21. In a machine of the class described, a shoe finishing tool for treating the upper 95 upon the side of the shoe, a shoe bottom rest, means arranged to begin operating said rest to beat the bottom of the shoe upon depression of the bottom rest, and a stop to limit the depression of the said rest.

100 22. In a machine of the class described, a shoe finishing tool, a work rest support, and a normally horizontally disposed work rest provided with means arranged to engage the shoe bottom between the feather edge and the lip of a welt innersole and hinged to the said support to permit the work rest to be tipped out of the horizontal together with a stop to limit the extent of such tipping movement.

110 In testimony whereof I have signed my name to this specification in the presence of two subscribing witnesses.

ORRELL ASHTON.
